[57] CLAIM

The ornamental design for a multi-flavor dispensing valve cover, as shown and described.

DESCRIPTION

FIG. 1 is a top, front, and left side perspective view of a multi-flavor dispensing valve cover showing our new design;

FIG. 2 is a front elevational view of FIG. 1;

FIG. 3 is a right side elevational view of FIG. 1;

FIG. 4 is a rear elevational view of FIG. 1;

FIG. 5 is a left side elevational view of FIG. 1;

FIG. 6 is a top plan view of FIG. 1;

FIG. 7 is a bottom plan view of FIG. 1;

FIG. 8 is a top, front, and left side perspective view of a modified form of our new design for a multi-flavor dispensing valve cover;

FIG. 9 is a front elevational view of FIG. 8;

FIG. 10 is a right side elevational view of FIG. 8;

FIG. 11 is a rear elevational view of FIG. 8;

FIG. 12 is a left side elevational view of FIG. 8;

FIG. 13 is a top plan view of FIG. 8; and

FIG. 14 is a bottom plan view of FIG. 8.

The broken line showing of the dispensing valve in FIGS. 1-5 and 8-12 is illustrative of environmental structure only and forms no part of the claimed design.
